UNITED STATES PATENT OFFICE.

OSCAR C. SCHMIDT, OF CINCINNATI, OHIO, ASSIGNOR TO THE CINCINNATI BUTCHERS' SUPPLY COMPANY, OF CINCINNATI, OHIO, A CORPORATION OF OHIO.

STUFFING MECHANISM.

Application filed December 29, 1920. Serial No. 433,792.

To all whom it may concern:

Be it known that I, OSCAR C. SCHMIDT, a citizen of the United States, residing in Cincinnati, in the county of Hamilton and State 5 of Ohio, have invented certain new and useful Improvements in Stuffing Mechanism, of which the following is a specification.

My invention relates to stuffing mechanism applicable among other things for stuffing 10 sausage casings.

It is the object of my invention to provide new and improved means for enhancing safety in manipulation of a device of this character; further, to provide novel means 15 employed in cleaning the interior of the mechanism and in supporting the safety means; further, to provide novel arrangement of means for counterbalancing the cover of the device; further, to provide novel 20 means for securing the cover in place and for employing the securing means to balance the cover when opening and closing the latter; further, to provide novel means for controlling the opening and closing of the 25 cover; and, further, to provide novel press-head mechanism in a device of this character.

The invention will be further readily understood from the following description and claims, and from the drawings, in which 30 latter:

Fig. 1 is a side elevation of my improved device, partly broken away for better illustration of parts.

Fig. 2 is a plan view of the same.

Fig. 3 is an end elevation of the same, 35 partly in central axial section, on the line 3—3 of Fig. 2, for better illustration of parts.

Fig. 4 is a side elevation of the pressure 40 safety mechanism of my improved device.

Fig. 5 is a front elevation of the same.

Fig. 6 is a horizontal section of my improved device taken in the plane of the line 45 6—6 of Fig. 7, partly broken away.

Fig. 7 is a central axial section of a detail 50 of my improved device, taken in the plane of the line 7—7 of Fig. 6, showing the press-head in lowermost position, with its packing in retracted relation.

Fig. 8 is a detail of the operated end of the 55 pressure safety mechanism, taken on the line 8—8 of Fig. 5.

Fig. 9 is a horizontal section of the same, taken in the plane of the line 9—9 of Fig. 8.

Fig. 10 is a central axial section of the 55 stuffing valve, taken on the line 10—10 of Fig. 2.

Fig. 11 is a vertical section of a detail of the securing mechanism for the cover, taken on the line 11—11 of Fig. 3.

Fig. 12 is a cross-section of the safety control valve for controlling the operation of the cover, taken in the plane of the line 60 12—12 of Fig. 13.

Fig. 13 is an axial section of the same, 65 taken in the plane of the line 13—13 of Fig. 12.

Fig. 14 is a sectional detail taken on the line 14—14 of Fig. 3; and,

Fig. 15 is an enlarged sectional detail of 70 the press-head.

A press-head is employed in mechanism of this character, operable in a cylinder, for the purpose of forcing plastic material, for instance, chopped and prepared sausage 75 meat or, as it is called, meat dough, through a nozzle or nozzles into so-called sausage casings. The meat dough is placed at one side of the press-head, while pressure, preferably fluid pressure, is employed at the other side 80 of the press-head, for forcing the material through the nozzle or nozzles. The pressure required depends in great measure upon the consistency of the meat dough or plastic material.

This is at times very great. It has 85 happened in operations of devices of this character that the press-head has been blown out of the cylinder by the pressure behind it. It is also desirable, in a device of this character, that the interior of the cylinder and the parts of the mechanism connecting therewith shall be readily accessible for the purpose of cleaning and attention to the parts.

I have also found it desirable to provide a 90 simple press-head employing few parts, and provided with a packing so arranged that its diameter will automatically decrease upon retraction of the press-head, and automatically increase in simple manner upon movement 95 of the press-head in opposite directions, for forming a close joint between the press-head and the inner face of the wall of the cylinder, to prevent the leaking of material being pressed and of the fluid of the pressure medium, past the press-head.

Having thus intimated the character of the improvements which I have invented in a device of the character mentioned, I shall 100 105

now more particularly describe an exemplification of the same, having reference to the exemplification shown in the drawings.

A casing 21 has a press-head 22 operable therein. The casing is shown as an upright cylinder. It has a bottom 23, suitably secured to the wall of the casing by bolts 24. A nozzle 25 communicates with the upper portion of the casing, as through a valve 26, having attachment, as by means of a threaded connection 27, with a port 28. The nozzle is releasable so that nozzles of various kinds may be attached, as by a threaded collar 29 threaded to the valve, and having an annular flange 30 coacting with an annular flange 31. A handle 32 is arranged to rotate the valve-plug, for opening and closing the valve, and thereby respectively forming communication between the interior of the casing and the nozzle, so as to fill a sausage or other casing slipped over the nozzle, or to regulate or cause cessation of the flow of filling material. I have shown a pair of such nozzles communicating with the casing, the parts of the respective nozzles being designated by similar reference numerals.

The plastic material or meat dough is placed in the casing above the press-head. The fluid pressure, for instance compressed air, water or steam, is introduced into the casing below the press-head, whereby the pressure thereby exerted acts to raise the press-head, and thereby force the plastic material through the nozzle. The fluid is exemplified as introduced into the casing through a port 35, with which a pipe 36 communicates, a valve 37 opening and shutting off or regulating the supply of pressure through the pipe, this valve being provided with safety control means for controlling the opening of the cover. The safety control means are exemplified as an arm 38, the arm and the valve-plug being operable by means of a handle 39, and acting in manner hereinafter more particularly described.

The casing is arranged to be closed by a cover 41, pivoted at 42 to the casing, as by means of providing the cover with a bearing 43 and the casing with bearing-lugs 44. The pivot-pin is received through the bearings of the bearing-lugs and the bearing of the cover for permitting swinging of the cover. There is preferably a taper joint 45 between the cover and the casing, so as to form a close joint between the same when the cover is closed.

A yoke 48 is pivoted on studs 49 extending from the casing or cylinder, as by having bearings 50 received about said studs. The studs have threaded connection 51 with lugs 52 on the casing. The yoke comprises arms 53 arranged to be received at the sides of the casing and a cross-piece 54 arranged to be received over the cover. The yoke is preferably substantially a heavy casting.

This yoke aids in counterbalancing the cover, in manner presently to be described, when it is desired to open the cover.

The cover is provided with a hump 57 having a contact-face 58, shown as an arc-face. The hump is shown on an arm 59 attached to the cover proper by bolts 60. The contact face corresponds substantially with the sector of the path of movement of the yoke-part adjacent thereto.

Means are provided for fixedly connecting the cover and the yoke when the cover is in closed position, accomplished, for instance, by providing the cover and the yoke with a coacting plug and recess. The recess is shown at 61 in the arm, and the plug is shown as a block 62 for instance, a round block fitting the recess, the plug being rotatively secured to a threaded clamping rod 63, having threaded connection with a bushing 64, secured, as by a set-screw 65, in the bearing 66 of the yoke. The bushing is provided with a flange 67 received in a recess 68 in the lower part of the bearing 66 for resisting the force of the pressure when clamping the cover. The plug is held to the threaded clamping rod by means of a screw 69, the clamping rod being preferably rotatable on said plug. Handles 71, preferably provided with weights 72, are fixed to the threaded rod for conveniently operating the same, and exerting force to force the cover toward the casing for firmly clamping the cover to the casing.

The cover is provided with a portion arranged to be acted upon by the yoke for aiding in counterbalancing the cover. This portion of the cover is at that side of the pivot for the cover opposite the side thereof at which the cover proper is located. This cover-portion is shown as an extension 75 of the arm 59, having a face 76 arranged to be contacted by the yoke when the yoke is moved into release position. This face is shown as a curved recess. The curve of this recess and the arc of curvature of the contact portion of the cover, are shown as forming an ogee-like contact-face, the outer end of which, in the present exemplification, forms a resting face for the yoke when the yoke is moved into extreme release position, as indicated in dotted lines in Fig. 1. The yoke is adapted to contact and move along the contact-face, and to rest on the rear portion of this face.

For further aiding in the operation of the cover in opening and closing the same, I provide a spring 78 between the rearward extension of the cover and a bracket 79 extending from the cylinder or casing. This spring is so positioned and located as to act as a cushioning means for the cover at the ends of the movements of the same when opening and closing the cover. This spring is shown as a tension spring, and is arranged

to be expanded during the final portion of the movement of the cover in closing the cover, so as to prevent shock when closing the cover, and also to be expanded during the final portion of the movement of the cover when the cover is opened, the opening and closing movements of the cover being thereby cushioned.

Referring to Fig. 1, the cover is shown in closed relation in full line, and in open relation in dotted lines. The arc of movement of the connection of the upper end of the spring with the cover is indicated by the dotted line *a*. The spring is at least resistance when the point of connection of the upper end of the spring with the cover is in a right line between the point of connection of the lower end of the spring and the bracket and the pivot of the cover, the axis 20 of the spring in such relation being indicated by the dotted line *b*. An arc which would be described by the upper end of the spring in such tension relation, having the connection of the lower end of the spring 25 as its center, is indicated by the dotted line *c*.

When therefore the connection between the upper end of the spring and the cover is moved to either side of the dotted line *a*, the tension of the spring is increased, thereby acting as a counter-balance cushion when opening or closing the cover. The cover swings to greater extent away from the vertical plane of its pivot when closing the 35 cover, causing a greater tension on the spring, and swings to less extent away from said vertical plane when placed in open relation, causing a less tension on the spring, the counterbalancing action of the spring 40 being therefore proportional to its duty. The end of the extension rests against the casing when the cover is open.

Referring to Figs. 1, 2, 3 and 11, the yoke is shown in its position for closed and 45 clamped relation of the cover, with the clamping rod screwed toward the cover for closed relation of the joint 45 between the casing cylinder and the cover. If it is desired to release the cover, the clamping rod 50 63 is turned for releasing its pressure on the cover and moving the block 62 out of the recess 61. The yoke may then be tilted, it being provided with a handle 81, which may be employed in operating and controlling 55 the swinging thereof. When the yoke is swung for opening of the cover, the yoke will move along the contact-face 58, as by contact of the block 62 therewith, the spring 78 acting to urge open relation of the cover 60 until its axis is coincident with the dotted line *a*. The cover is provided with a grip 82 by means of which the cover may be moved in opening and closing the same.

As the upper end of the yoke moves rearwardly, it is received in a recess 83, to rear

of the pivot of the cover, and makes contact with the face 76, as by means of the bolt 65. Opening movement of the cover causes further descent of the upper outer end of the yoke, for causing the yoke to move along the contact-face 76, thereby aiding in counterbalancing the cover and permitting opening of the cover with little exertion. The parts are preferably arranged so that the action of the spring 78 and the weight of the swinging end of the yoke, when the latter contacts the face 76, are sufficient to further tilt the cover into open relation with little or no exertion, the weight of the cover if desired, being supplemented by forward stress on the grip 82, the final opening movement of the cover being cushioned by the spring 78. When the cover has been tilted into full open relation, its swinging end is preferably in rear of the vertical plane in which the pivotal axis of the cover is located.

When it is desired to close the cover, the swinging end of the yoke is raised and the cover is swung toward closing position. 90 The spring 78 acts initially as an aid to the closing movement, until the swinging end of the cover passes the vertical plane in which the pivot of the cover is located, and then acts as a cushion to resist shock in closing the cover. The cover may be manipulated by means of the grip. When the cover has been lowered, the swinging end of the yoke may be still located adjacent the rear end of the contact-face 58, adjacent the pivot of the cover. The swinging end of the yoke is moved over the cover, its block 62 moving along the contact-face 58, aiding in urging closing relation of the cover.

The yoke is provided with a stop 85 arranged to coact with a stop 86 on the cover, the latter being shown as a lug on the arm 59, for limiting swinging movement of the yoke and positioning the clamping screw thereon with relation to the recess therefor in the cover. The clamping screw is then turned for clamping the cover in place and securely closing the joint 45 between the cover and the casing.

It is assumed that the casing has been provided with its desired amount of plastic material, for instance, meat-dough, prior to the closing of the cover.

The valve 37 has in the meantime been placed in closed relation. In order to supply pressure to the under side of the press-head, the valve 37 is turned into open relation, whereby the arm 38 is moved across the path of the yoke 48, to prevent reopening of the cover while pressure is being exerted through the valve, the arm of the yoke in this relation being located between said arm 38 of the valve and the stop 85. The yoke cannot therefore again be swung for open relation of the cover until after the

valve 37 has been turned into closing position, whereby the arm 38 is moved out of the path of the yoke.

The valve 37 is shown as a conical valve, 5 having a conical valve-plug 87 received into the conical socket of the valve body 88.

The handle 39 and the arm 38 are shown 10 as one piece in fixed relation to the valve-plug. A supply pipe 89, leading from any suitable source of pressure, for supplying a fluid, which may be air, water, steam or other desirable pressure medium, connects with the valve 37, and has a pressure regulating valve 90 therein. The valve-body 15 of valve 37 has a port 91, with which the pipe 89 connects, a port 92, with which the pipe 36 connects, and a port 93 which communicates with the atmosphere. The valve-plug has ports 94, 95, 96. When the ports 20 91, 94, 95, 92, are in registry, pressure is being supplied to the press-head, and the arm 38 is in obstructing relation to the yoke. A pin 97 limits movement of the arms of the valve 37. When the ports 92, 96, 95, 93, are 25 in registry, the space in the casing under the press-head is open to the atmosphere.

Convenient means are provided for cleaning the cylinder or casing. Descent of the press-head is limited by stops 101, shown 30 as posts located in the bottom of the casing. The casing is further provided with a cleaning opening 102, which is arranged to be closed by a cap-plate 103, by means of bolts 104.

35 Safety means are provided in connection with the cleaning means. The safety means comprise a valve 105, (See Figs. 1, 3, 4, 5, 6, 7, 8 and 9) which coacts with a valve-seat 106, located in the cap-plate 103, of the cleaning device. The cap-plate is shown 40 provided with a tube 107, and the valve-stem 108 is provided with guide-wings 109 co-acting with the inner guide-face of the tube. A cross-piece 110 is secured to the cap-plate, 45 as by means of bolts 111, having sleeves 112 thereover. The sleeves are located between the cap-plate and the cross-plate for relatively positioning the same, nuts 113 being received over the ends of the bolts for clamping the parts rigidly together. These parts extend inwardly of the cap-plate. The valve 50 is provided with an inwardly extending guide-stem 114, guided in a bearing 115 in the cross-plate. A spring 116 is received 55 thereover between the valve and the cross-piece for normally urging the valve into closed relation.

The valve is arranged to be actuated by 60 the press-head when the latter reaches a danger position or limit of movement in upward direction. These means are shown as comprising a lever 121 pivoted by a bolt 122 to a bracket 123 extending from the casing, and having a trip 124 articulated 65 therewith at 125. The trip is shown as an

axially movable rod, movable in a bearing 126. A packing 127, located in a socket 128, surrounds the trip. A gasket 129 has bolts 130 threaded into the casing, acting to compress the packing. The trip has a contact-face 131, shown as a slanting face, arranged to be contacted by the press-head, for moving the trip axially when the press-head is adjacent its upper limit of movement, thereby swinging the lever 121, and moving the valve 105 axially into open relation, in order to relieve pressure in the cylinder or casing under the press-head, and thereby acting to cause cessation of outward movement of the press-head. The inner end of the trip 75 is preferably located in a recess 132 in the cover, the slanting face of the trip being continued in the recess. 80

The movement of the trip by the press-head, upon contact of the lower portion of the inclined contact face of the trip by the press-head, is sufficient to relieve pressure under the press-head sufficiently to avoid damaging contact between the press-head and the cover. If, however, the cover should be open either partly or wholly and the press-head be urged rapidly upwardly, whereby it is caused to contact the trip, the trip will be moved an additional distance, 90 represented by the portion of the inclined face thereof in the recess 132, thereby opening the valve 105 to greater extent, and creating additional relief under the press-head sufficient to prevent thrust of the press-head out of the cylinder. 95

An adjustable stop 135 is provided for this safety mechanism, shown as a bolt 136 threaded into a lug 137 in the casing and having a threaded tube 138 thereabout, the outer end of which is arranged to be contacted by the lever 121, for limiting movement of the lever in its direction of release position, and limiting inward movement of the trip, the nut being adjustable on the bolt 105 for adjusting these limits of movements. 110

The press-head in its preferred form comprises an upper section 141, and a lower section 142, (See Figs. 3, 7 and 15). One of these sections, shown as the section 142, is provided with an annular rabbet 143, in which a band 144 is received. This band is a compressible and extensible band, and is preferably elastic. This elastic band is preferably of rubber, or of a composition having rubber as a base. The opposite section of the press-head is provided with an annular flange 145, the inner face of which is arranged to be received about the cylindrical face of the rabbet. 115

The elastic band is received in the annular rabbet between the flange 145, which forms a shoulder therefor, and a shoulder 146 forming one of the end walls of the rabbet. The annular flange 145 is provided with an outer annular lip 147, and the 120 125 130

shoulder 146 is provided with an outer annular lip 148, respectively received in annular rabbets 149, 150, at the respective ends of the annular flexible band.

5 The lower section is shown provided with a recess 151, in which an enlargement 152 of the other section is arranged to be received. Means are provided for limiting separating movement between the sections, 10 shown accomplished by a bolt 155 threaded into the lower section and received through a bearing 156 in the upper section. The upper end of the bolt is located in a recess 157 in the upper section. A nut 158 is adjustably received in the recess over the bolt. 15 Adjustment of the nut lengthwise of the bolt adjusts the extent of separating movement between the sections, as will be noted by comparison between Figs. 3 and 7. The 20 upper end of the bolt and the nut have reciprocating movement in this recess.

Contact between the plastic material and the adjustable limiting means is avoided by providing a plug 159 having threaded engagement with the outer end of the wall of the recess 157. A gasket 160 is clamped by the plug against an annular shoulder 161 formed in the recess. The plug may be turned by a suitable square-ended wrench 30 received in a hole 162 of square cross-section in the plate.

The lower-section of the press-head is shown as of greater weight than the upper section, so as to insure a dropping of the lower section with relation to the upper section. The annular elastic band 144 is received about the inner wall of the rabbet 143, so that, when the sections of the press-head are in separated relation, the elastic band will be in stretched relation in said rabbet, and preferably within the cylindrical projection of the press-head. This relation of parts is shown in Figs. 7 and 15, in which the press-head is shown at its lowermost limit of movement.

Plastic material having been placed in the casing above the press-head, and the cover closed and clamped, pressure is supplied under the press-head through the valve 26. 50 The pressure acts against the lower face of the lower section of the press-head, raising this lower section, resisted by the annular band or ring, whereby the elastic band is compressed in axial direction for reducing the width of said elastic band and increasing its thickness, that is to say, its thickness and diameter are increased or spread for forcing it into intimate contact with the inner cylindrical face of the cylinder, to form a tight joint between the press-head and the wall of the cylinder, in order to avoid passage of the pressure fluid upwardly past the plastic band and passage of plastic material downwardly past the elastic band.

When the band has thus been acted on by the upward pressure on the lower section of the press-head sufficiently to support the upper section of the press-head and the weight of the plastic material thereabove, 79 the press-head will move upwardly, with the sections of the press-head in closer relation and the elastic band in spread relation, as indicated in Fig. 3. The upward movement of the press-head will force the plastic material through the nozzle or nozzles.

When the upward movement of the press-head has been completed, and the valve 26 is closed to the supply of pressure and opened to the atmosphere, the lower section of the press-head will drop to the limit of the permitted separation by means of the bolt 155 and nut 158, whereby the thickness and diameter of the elastic band are again reduced to substantially the relation shown in Figs. 7 and 15, for permitting descent of the press-head in the cylinder to follow the release of pressure in said cylinder.

The cover may then be again opened for recharging the casing with additional plastic material, for repetition of the operation.

The elastic band is made of such composition, for instance with a rubber base, that the liquids in the meat dough or sausage filling and the cleaning operations will not crack or harden the same, experience having demonstrated that with my improved construction the elastic band retains its life and is effective in operation for a very extended period of time.

I do not herein claim the press-head herein shown and described, having shown, described and claimed the same in my pending application for Letters Patent of the United States on improvements in press-heads for stuffing machines, duly filed in the United States Patent Office February 13, 1923, as Serial No. 618,877, and as a division of the present application.

Having thus fully described my invention, what I claim as new, and desire to secure by Letters Patent, is:

1. In mechanism of the character described, the combination of a casing, a press-head in said casing, a cover for said casing at one side of said press-head, a pressure outlet for said casing at the other side of said press-head, a closure for said pressure outlet, an operating part for said closure received in said cover, and connecting means between said operating part and said closure.

2. In mechanism of the character described, the combination of a casing, a cover therefor, a press-head in said casing, a pressure outlet, a closure therefor, an operating part for said closure operable in said casing, and connecting means between said operating part and said

closure, said cover provided with a recess for said operating part and said operating part provided with an operating face acted on by said press-head, said operating face being partially located below the plane of said cover and partially located within the plane of said cover when said cover is closed, and adapted for actuation to different extents by said press-head when said cover is open and when said cover is closed.

3. In mechanism of the character described, the combination of a casing, a cover therefor, a press-head operable in said casing, a pressure outlet in said casing, a closure therefor, an operating part, and connecting means between said operating part and said closure, said operating part provided with an operating face for coaction with said press-head to different extents when said cover is in closed position and when said cover is open.

4. In mechanism of the character described, the combination of a casing, a cover therefor, a press-head operable in said casing, a cleansing opening in said casing at one side of said press-head, a cap therefor, a pressure relief opening in said cap, a closure therefor, and contact means for said press-head having operative connection with said closure for opening the same.

5. In mechanism of the character described, the combination of a casing, a press-head operable therein, a cleansing opening, a cap therefor, said cap provided with a pressure relief opening, a valve therefor, a cover for said casing, an axially movable trip in said casing at said cover, and a lever having operative connection with said casing, said trip and said valve.

40 6. In mechanism of the character described, the combination of a casing, a press-head operable therein, said casing having a cleaning opening at one side of said press-head, a closing cap for said cleaning opening, a pressure relief opening in said cap; valve mechanism therefor including a valve-stem, a bearing strip for said valve stem, means for securing said bearing strip in distanced relation to said cap, and a spring between said bearing-strip and said valve normally closing said valve; and stopping means in said casing limiting approach of said press-head toward said valve mechanism, said valve mechanism extending into 55 the projections of the lines of movement of said press-head.

60 7. In mechanism of the character described, the combination of a casing, a press-head operable therein, a cover for said casing, means for hinging said cover to said casing, and a counterbalancing spring for said cover, said counterbalancing spring having connection with said cover to counterbalance said cover upon both the open-

ing movement and the closing movement of 65 said cover.

8. In mechanism of the character described, the combination of a casing, a press-head operable therein, a cover for said casing, means for hinging said cover to said casing, said cover provided with an extension extending beyond the pivotal axis of said cover, a spring, a stationarily positioned connection for said spring, and a connection between said spring and said extension, said last-named connection movable to both sides of a right line between said stationarily positioned connection and the pivotal axis of said cover by the respective opening and closing movements of said cover, whereby to cushion said cover at both its opening and closing movements.

15 9. In mechanism of the character described, the combination of a casing, a press-head operable therein, a cover for said casing, means for hinging said cover to said casing, a yoke received crosswise of said cover, said cover provided with a contact-face for coaction with said yoke, said contact-face extending lengthwise of the path 20 of movement of said yoke, and clamping means between said yoke and said cover to clampingly close said cover.

25 10. In mechanism of the character described, the combination of a casing, a press-head operable therein, a cover for said casing, means for hinging said cover to said casing, said cover provided with an extension beyond its pivotal axis, and a yoke pivoted to said casing and extending crosswise of said cover, said extension having 30 resting means for said yoke.

35 11. In mechanism of the character described, the combination of a casing, a press-head operable therein, a cover for said casing, means for hinging said cover to said casing, a yoke pivoted to said casing and received crosswise of said cover, said cover provided with an extension beyond its 40 pivotal axis, said extension provided with a resting portion for said yoke, and resilient cushioning means having connection with said extension to cushion the movement of said cover.

45 12. In mechanism of the character described, the combination of a casing, a press-head operable therein, a cover for said casing, means for hinging said cover to said casing, a yoke pivoted to said casing and straddling said cover, and clamping means 50 between said yoke and said cover, said cover provided with an extension, said extension provided with a resting portion for said yoke, whereby said yoke coacting with said resting portion aids in counterbalancing said 55 cover.

60 13. In mechanism of the character described, the combination of a casing, a press-

head operable therein, a cover for said casing, means for hinging said cover to said casing, a yoke pivoted to said casing and straddling said cover, clamping means between said yoke and said cover, said cover provided with an extension, said extension provided with a resting portion for said yoke, whereby said yoke coacting with said resting portion aids in counterbalancing said cover, a spring, a stationarily positioned connection for one end of said spring, and a connection between the other end of said spring and said extension, and arranged whereby said last-named connection moves to both sides of a right line between said stationarily positioned connection and the pivotal axis of said cover upon the opening and closing movements of said cover.

14. In mechanism of the character described, the combination of a casing, a press-head operable therein, a cover for said casing, means for hinging said cover to said casing, said cover provided with an extension beyond the pivotal axis of said cover, and a yoke pivoted to said casing and straddling said cover, clamping means on said yoke, said cover provided with a convexly curved contact face at one side of its pivotal axis and said extension provided with a concavely curved contact face at the other side of said pivotal axis, and said contact faces coacting with said yoke, and said yoke aiding in counterbalancing said cover when in coactive relation with said extension.

15. In mechanism of the character described, the combination of a casing, a press-head operable therein, a cover for said casing, means for hinging said cover to said casing, a yoke pivoted to said casing and straddling said cover, clamping means on said yoke, said cover provided with a coacting face coacting with said clamping means and extending lengthwise between the pivotal axis of said cover and the swinging end of said cover, and a stop on the swinging end of said cover for said yoke.

16. In mechanism of the character described, the combination of a casing, a press-head operable therein, a cover for said casing, pressure supply means for said press-head including a valve, a yoke pivoted to

said casing and received crosswise of said cover, and an obstructing part having connection with said valve for location in obstructing relation in the path of movement of said yoke upon open relation in said valve.

17. In mechanism of the character described, the combination of a casing, a press-head operable therein, a cover for said casing, pressure means for said press-head including a valve, a yoke pivoted to said casing and extending crosswise of said cover, and an obstructing part having operative connection with said valve whereby said obstructing part is obstructingly placed in the path of said yoke when said valve is open and whereby said obstructing part is moved to be free of obstructing relation in the path of movement of said yoke when said valve is closed.

18. In mechanism of the character described, the combination of a casing, a press-head operable therein, a cover for said casing, means for hinging said cover to said casing, a yoke pivoted to said casing and straddling said cover, pressure means for said press-head including a valve, and an arm operable with said valve into obstructing relation in the path of movement of said yoke by opening said valve and free of such obstructing relation by closing the said valve.

19. In mechanism of the character described, the combination of a casing, a cover therefor, a press-head operable in said casing, a pressure outlet in said casing, a closure therefor, an operating part, and connecting means between said operating part and said closure, the said press-head and the said operating part having parts thereon relatively so formed whereby to operate said closure by means of said press-head to different extents when said cover is in closed position and when said cover is open.

In testimony whereof, I have hereunto signed my name in the presence of two subscribing witnesses.

OSCAR C. SCHMIDT.

In presence of:—

JAMES J. FITZPATRICK,
DELMA WERNING.
